UNITED STATES PATENT OFFICE.

WINFIELD P. PEMBROKE, OF ROCHESTER, NEW YORK.

CARBURETER.

1,192,106.

Specification of Letters Patent. Patented July 25, 1916.

Application filed March 16, 1914. Serial No. 824,885.

To all whom it may concern:

Be it known that I, WINFIELD P. PEMBROKE, of Rochester, in the county of Monroe and State of New York, have invented 5 certain new and useful Improvements in Carbureters; and I do hereby declare the following to be a full, clear, and exact description of the same, reference being had to the accompanying drawings, forming a part 10 of this specification, and to the reference numerals marked thereon.

My present invention has for its object to provide an arrangement of parts adapted to be incorporated in the construction of carbureters such as those used for supplying the explosive mixture for explosive motors or engines, and it has for its primary object 15 to provide an arrangement of inlets, or passages, for the liquid fuel and air in conjunction with a deflecting surface whereby the stream of liquid fuel is thinned out, or attenuated and caused to form a carbureted mixture with the inrushing air by reason of 20 the contact of both of said elements with 25 said surface.

My invention has for its further object to provide a valve mechanism by means of which the flow of air and liquid fuel may automatically be controlled and proportioned by the pressure of the inrushing air admitted to the carbureter.

To these and other ends the invention consists in certain improvements and combinations of parts all as will be hereinafter more 30 fully described, the novel features being pointed out in the claims at the end of the specification.

In the drawings: Figure 1 is a cross-sectional view of a carbureter casing illustrating 40 a mechanism constructed in accordance with my invention applied thereto; Fig. 2 is an enlarged detail sectional view showing a valve head in the open position; Fig. 3 is a similar view of the valve head illustrating the use of 45 weights for restraining its opening movement, and Fig. 4 is a detail sectional view of a modification illustrating the deflecting surface arranged stationary relatively to the air and fuel inlets.

50 Similar reference numerals in the several figures indicate the same parts.

My invention comprehends an arrangement of parts applicable to a carbureter of the usual or any preferred construction, and 55 for the purposes of illustration I have shown a device of this nature comprising the hol-

low casing, forming the vaporizing chamber 2 from which the outflow of carbureter mixture is controlled by a throttle valve 3. The usual air inlet valve is shown comprising the 60 head 4, coöperating with the seat 5 and carried on the stem 6, surrounded by the coil spring 7 which serves to normally hold the valve head 4 in the closed position, said spring being adjustable so that the valve 65 head may automatically open when the desired partial vacuum is produced in the chamber 2.

In illustrating my invention I have shown a combined air and liquid fuel nozzle opening into the bottom of the chamber 2 comprising a head 8 on the tube 9, which latter, it will be understood, is connected with the float chamber 10. The head 8 comprises a circumferential air inlet passage A within 70 which is disposed the liquid fuel inlet B, the outer open end of which is preferably tapered slightly, as shown, to form a seat in which is fitted a conical projection, or valve member b, carried on the lower side of a disk 80 10^a which may be utilized as a valve head and mounted to coöperate with the flattened face, or seat provided on the nozzle or head 8. The disk 10 is carried upon a rod 11 guided in a threaded sleeve 12, vertically adjustable in the top of a casing 1 for the purpose of regulating the tension of the coil spring 13 which surrounds the stem 11 and serves to normally hold the valve head 10 in the closed position, as shown in Fig. 1. In 90 lieu of the spring 13, weights in the form of washers indicated by 12^a and illustrated in Fig. 3, may be used as it is merely desired to provide adjustable means for retarding the movement of the valve head 10^a by offering a given predetermined resistance to its 95 opening movement, which will only be overcome when the desired suction or partial vacuum has been created in the mixing chamber 2. The valve head 10^a performs the dual function of closing both the air and fuel inlets and of forming the deflecting surface against which the air and fuel currents impinge when the valve is in its open positoin. When the difference in pressure between the partial vacuum produced 100 in the chamber 2 and the external atmosphere is sufficient to overcome the resistance of the spring 13, the air currents seeking to enter the chamber 2 through the air inlet A will cause the valve head 10^a to 110 be opened to a greater or less extent, as

shown in Fig. 2. These inrushing air currents are in the form of a tubular column, the top of which engages against the under surface of the disk 10^a and is deflected laterally and annularly and so long as the pressure is constant the air currents support the valve head at a given distance from the face of the nozzle 8, which distance is increased with an increase of pressure, or decreased when the pressure is lessened, so it may be said that the opening movement of the valve head is proportional to the difference between the atmospheric pressure and that contained in the chamber 2.

The fuel inlet B is disposed within the air inlet, or otherwise arranged, in such a manner that the fuel escaping therefrom is obliged to pass through or cross over the column of inrushing air, the twofold purpose of which is to cause the liquid fuel to be attenuated while it is still in its liquid state, by contact with the deflecting surface and to be thoroughly mixed with the air currents by contact with the latter at the point where said air currents engaged the deflecting surface and from which point the air and fuel in vaporized condition pass off together as the carbureted mixture. The proportion of the fuel admitted in relation to the quantity of air flowing through the inlet A is controlled by the valve head projection b which is preferably made conical to provide not only for easy and delicate contact of the fuel, but also to serve as a means for dividing the fluid column emitted from the nozzle B and direct it laterally in all directions. By observation of the illustration shown in Fig. 2 it will be seen that the column of gasoline or other hydrocarbon fluid is divided by the point of the projection b and traveling upward engages against the deflecting surface of the valve head 10, which causes it to be splayed into a mushroom shape, or canopy, at the edge of the deflecting surface where the fuel sheet becomes thin the inrushing air column impinges against it producing the further effect of attenuating said liquid sheet and immediately creating it into a vapor which is directed laterally, in the presence of the moving air currents and away from the annular edge of the deflecting surface.

In Fig. 4 I have shown a modification of the parts previously described, illustrating the deflecting surface as being in the form of a stationary projection 100 extending over an air inlet passage A' and fuel inlet passage B' the former being arranged as a semi-circular opening inclosing the outlet B' so that the fuel ejected therefrom in

order to escape from beneath the flange 100 is obliged to cross between said flange and air jet rushing inwardly through the aperture A'.

A fuel vaporizing mechanism comprising my invention is automatic in its operation, as it is controlled entirely by the air pressure seeking admittance into the carbureter casing and the supply of liquid fuel and air are always proportioned to each other and the quantity of each of these elements delivered is at all times of the exact amount demanded by the engine, or motor, with which the carbureter is associated. Furthermore, the mechanism consists of few parts which are simple in their arrangement and are adapted to be applied to the vaporizing chamber of carbureters of the usual, as well as any preferred, construction.

I claim as my invention:

1. In a carbureter, the combination with a casing in which a partial vacuum is maintained, of a head insertible through a wall of the casing and having a reduced tubular extension positioned exteriorly of the casing forming a fuel inlet communicating with said casing, said head having air inlets formed therethrough communicating with the casing and terminating outwardly substantially at a point where the tubular extension connects with said head, and a valve normally closing the inlets and adapted to be opened by air currents passing through said air inlets and serving, when opened, to deflect the liquid current into the path of the air currents.

2. In a carbureter, the combination with a casing in which a partial vacuum is maintained, of a head inserted in the wall of the casing having a plurality of air inlets therein and provided with a centrally disposed fuel inlet and a valve normally closing the fuel and air inlets and adapted to be opened by air currents passing through the air inlets.

3. In a carbureter, the combination with a casing in which a partial vacuum is maintained, of a head inserted in the wall of the casing having a plurality of air inlets therein and provided with a centrally disposed inwardly tapering fuel inlet and a valve normally closing the air inlets and adapted to be opened by air currents entering the latter and having a pin projecting into the fuel inlet.

WINFIELD P. PEMBROKE.
